PRODUCTION OF CHLORINATED HYDROCARBONS.

1,231,123.

Specification of Letters Patent. Patented June 26, 1917.

Application filed December 10, 1915. Serial No. 66,068.

To all whom it may concern:

Be it known that we, BENJAMIN T. BROOKS and DILLON F. SMITH, citizens of the United States, residing at Pittsburgh, 5 Allegheny county, State of Pennsylvania, have invented certain new and useful Improvements in Production of Chlorinated Hydrocarbons; and we do hereby declare the following to be a full, clear, and exact 10 description of the invention, such as will enable others skilled in the art to which it appertains to make and use the same.

This invention relates to the production of dichlorinated hydrocarbons of the ethylene series, and particularly to the production of mixtures of dichlorinated hydrocarbons containing dichlor-ethylene and dichlor-propylene from mixtures of ethylene hydrocarbons containing ethylene and 20 propylene.

Oil gas, when suitably produced, is rich in olefins, particularly in the olefins of the ethylene series. The average oil gas produced, for instance, by Young's process, may 25 have a composition of about 43% olefins, 16% hydrogen and 30% to 33% saturated hydrocarbons, particularly methane. The composition will vary with the conditions under which the oil is produced, and the oil 30 gas may accordingly contain increased or decreased amounts of the olefins and saturated hydrocarbons. The oil gas may, for instance, contain about 33% unsaturated hydrocarbons, about 20% hydrogen and about 35 45% saturated hydrocarbons.

The olefins or unsaturated hydrocarbons of oil gas consist principally of ethylene and propylene. Relatively small amounts of other hydrocarbons such as butylene, amy- 40 lene, benzol, etc., may also be present. The relative proportions of ethylene and propylene, which are the principal unsaturated constituents, will also vary with different oil gases, depending upon the method of pro- 45 duction of the oil gas, the material from which produced, etc. For some purposes it is desirable that the gaseous mixture should contain relatively larger amounts of ethylene, while for other purposes larger 50 amounts of propylene may be desirable. The relative amounts of ethylene and propylene can also be varied and to a cer-

tain extent regulated by the method of producing the oil gas.

The present invention relates to the production of dichlorinated hydrocarbons of the ethylene series, and particularly to mixtures of dichlor-ethylene and dichlor-propylene, or mixtures consisting principally of these two chlorinated hydrocarbons. by 55 chlorinating the mixture of unsaturated ethylene hydrocarbons obtained from oil gas, after these hydrocarbons have been subjected to a suitable preliminary treatment.

According to the present invention, the 60 oil gas is first treated to separate the unsaturated hydrocarbons from the saturated hydrocarbons and hydrogen, and also to separate the ethylene and propylene from the other unsaturated hydrocarbons. For the 65 purpose of effecting this preliminary separation of the ethylene and propylene, the oil gas is, with advantage, subjected to a low temperature, such as is obtainable by combined cooling and compression, or by cooling 70 with or without pressure to sufficiently low temperatures, for example, in an apparatus similar to that used for the production of liquid air. The easily condensable constituents are thereby condensed out while other 75 constituents, particularly hydrogen and methane, remain uncondensed and are thus separated. The condensed gases are then slowly vaporized and the ethylene and propylene are slowly boiled off, leaving behind the hydrocarbons of higher boiling 80 point. Those higher boiling hydrocarbons will tend to boil off to some small extent with the ethylene and propylene, but the process 85 can be readily controlled so that the ethylene and propylene will be given off in a relatively pure condition, containing only small amounts of other hydrocarbons such as butylene.

In this manner, a mixture of the ethylene 90 hydrocarbons is obtained relatively free from hydrogen and methane, and also relatively free from higher boiling hydrocarbons both of an unsaturated and of a saturated nature. The removal of these hydrocarbons is of advantage for reasons which 100 will be presently pointed out.

The mixture of ethylene hydrocarbons is then chlorinated in order to convert them

into their corresponding dichlorinated derivatives. For this purpose, the gaseous mixture and chlorin are separately passed into a suitable co-solvent, *i. e.*, a solvent for 5 both the chlorin and the unsaturated hydrocarbons. As such co-solvents may be mentioned chloroform, carbon tetrachlorid, carbon disulfid, tetrachlorethane, and particularly the mixture of dichlorinated ethylene 10 hydrocarbons which results from the chlorinating process itself. As such co-solvents may be used any suitable solvent which will take up chlorin without being acted upon and which will also take up the hydrocarbons to be chlorinated.

The co-solvent also acts as a diluent and as a solvent medium for the reacting chlorin and hydrocarbons so that the chlorination reaction proceeds smoothly and in a manner 20 which can be readily controlled. The co-solvent is furthermore miscible with the chlorinated hydrocarbons resulting from the reaction so that the addition thereto of these further amounts of the chlorinated hydrocarbons formed is of advantage for the reason that the body of the co-solvent is thereby increased. As the amount of chlorinated hydrocarbons increases, part of the mixture of such hydrocarbons with the co-solvent, 25 where the co-solvent is other than the hydrocarbon mixture produced or of the hydrocarbon mixture, where this is used as the co-solvent, can be drawn off either in a continuous or in an intermittent manner.

30 The chlorination reaction results in the production of considerable heat, although the reaction is not of a violent nature. This heat will be first taken up by the body of liquid which forms the co-solvent. In order that this solution may not become too hot due to self-heating, it may be necessary or advisable to keep the solution cold by suitable cooling coils or cooling jackets. The reaction can, in fact, be carried on smoothly, 40 and in a manner readily controlled, at the ordinary temperature, or at colder temperatures, and at atmospheric pressure. In order to promote the uniformity of distribution of the chlorin solution throughout the body of 45 the co-solvent, suitable mechanical stirrers or agitators may be used, although the gases introduced will themselves tend to keep the solvent more or less agitated.

The concentration of the chlorin in the 50 co-solvent is maintained by continually passing in further amounts of chlorin in a finely divided condition as through small, practically capillary, apertures. The hydrocarbon mixture can be similarly introduced, 55 although the chlorin and hydrocarbon should not be introduced at the same place. Their introduction should be sufficiently separated so that solution will take place before the gases are brought into reacting 60 relation with each other.

During the chlorination, any saturated hydrocarbons such as ethane or propane will tend to pass through the solution and escape therefrom as vapors, since the saturated hydrocarbons are not acted upon by the 70 chlorin under the conditions of the reaction.

The chlorin used for the chlorination can be obtained from any suitable source, and moist chlorin has been found to give good results in the process.

75 The gases which escape from the chlorinating vessel consist of the saturated hydrocarbons which are not acted upon together with any unsaturated hydrocarbons which have escaped chlorination and any vapors 80 of chlorinated hydrocarbons which have been carried over with the unchlorinated hydrocarbons.

The escaping gases can be treated in a scrubber, with heavy hydrocarbon oils, for 85 the recovery of the chlorinated hydrocarbons; or they can be subjected to compression for the purpose of liquefying these hydrocarbons.

A suitable apparatus for the practice of 90 the chlorinating reaction of the present invention is indicated, more or less diagrammatically, in the accompanying drawings. The tank 1, which may be of earthenware, or other chlorin-resisting material, is provided with cooling coils 2 and with inlet 3 and outlet 4 for the introduction of the solvent and the removal of the solvent and of the chlorinated hydrocarbons. A suitable source of chlorin is indicated at 5, 95 from which the chlorin is introduced into the co-solvent by means of a perforated ring 6 having minute perforations therein of practically capillary size. The hydrocarbon gas enters through the gas supply pipe 7 100 and a similar distributing ring 8. From the top of the reaction vessel, the vapors escape through the pipe 9, either through the pipe 10 to the scrubber 11, or through the pipe 12 to the compressor 13. The scrubber may 105 be of any suitable construction so that the chlorinated hydrocarbons will be removed therein, as by means of heavy hydrocarbons flowing down through the scrubber. These chlorinated hydrocarbons carried over with 110 the vapors can be similarly removed by the compressor 13 and thereby separated from any accompanying gaseous hydrocarbons.

115 The arrangement of the chlorin and hydrocarbon inlets is such that the chlorin is 120 first absorbed before it is mixed with the hydrocarbon gases, the gas inlets being indicated as arranged a distance of, for example, 12 or 15 inches above the chlorin inlets, for this purpose.

125 The use of the mixture of dichlorinated hydrocarbons produced during the reaction, as a co-solvent, is of particular advantage, for the reason that no further separation of the product of the reaction therefrom is nec- 130

essary, and also for the reason that such a mixture appears of particular advantage as a solvent for the chlorin and for the hydrocarbons, and for the production therefrom of the chlorinated hydrocarbon mixture itself, which results from their combination. Where a co-solvent other than the chlorinated ethylene hydrocarbons is used, tetrachloroethane presents the advantage of having a boiling point considerably higher than that of the dichlor-ethylene and dichlor-propylene, so that these latter designated hydrocarbons can be readily separated by distillation.

Attempts have heretofore been made to produce mixtures of dichlorinated ethylene hydrocarbons from oil gas, but such production has, so far as we are aware, been accompanied by the production, at the same time, of other chlorinated derivatives from other unsaturated hydrocarbons and the production of hydrochloric acid from hydrogen, because of the fact that the hydrocarbon mixture chlorinated contained hydrogen and other unsaturated hydrocarbons. Where hydrogen is present, its chlorination, in some cases, takes place with explosive violence. Its chlorination, furthermore, to produce hydrochloric acid, involves a loss and waste of chlorin inasmuch as hydrochloric acid is relatively less desirable and valuable, and can be produced more readily by other processes. Furthermore, when hydrochloric acid is produced, it requires to be separately recovered and its presence appears to be prejudicial during the reaction and in the resulting product.

Furthermore, the presence of higher chlorinated hydrocarbons is undesirable in the product of the reaction where this product is to be used as a solvent or for other purposes, inasmuch as these higher chlorinated hydrocarbons split off hydrochloric acid readily. Their presence, because of their instability, is accordingly undesirable for many purposes.

The process of the present invention has the advantage over such prior proposals in that the ethylene hydrocarbons are first obtained relatively free from hydrogen and saturated hydrocarbons and from the higher unsaturated hydrocarbons, so that the resulting chlorinated product consists principally of a mixture of ethylene and propylene dichlorids. This product is a valuable product for use as a solvent, and forms an improved "Dutch" liquid. It can also be used for the production of glycols. For the production of an improved "Dutch" liquid, it is usually desirable to have the mixture relatively richer in propylene dichlorid. The relative amounts of these hydrocarbons in the mixture chlorinated can be to some extent regulated by regulating the process of producing the oil gas, as already stated.

The chlorination of the mixture of ethylene hydrocarbons, consisting principally of ethylene and propylene appears to proceed in a manner equally well or even more advantageously than the chlorination of the individual hydrocarbons, and accordingly, we consider the chlorination of such a mixture to produce a resulting mixture consisting principally of ethylene and propylene dichlorids, as a particularly valuable and important embodiment of our invention. The chlorination of the individual ethylene hydrocarbons can, however, be effected in a similar manner, and similar advantages obtained as with the chlorination of the hydrocarbon mixtures.

Inasmuch as the ethylene hydrocarbons are themselves unsaturated, the chlorination reaction is a simple addition reaction so that no other products of the reaction are produced. By carrying on the reaction in the cold or at ordinary temperatures and by the use of the co-solvent for promoting the reaction, the reaction proceeds smoothly in an easily regulated manner. No catalysts for promoting or modifying the reaction are necessary, and none need in practice be used, inasmuch as the reaction proceeds smoothly and in a particularly advantageous manner under the conditions described.

The mixture of dichlorinated hydrocarbons is obtained in a relatively pure condition, as above noted, being relatively free both of hydrochloric acid and of higher chlorinated hydrocarbons. No further purification will usually be necessary where the mixture is to be used for the production of glycols. Where the mixture is to be used as a solvent, it may be necessary or desirable to neutralize any small amounts of hydrochloric acid which may be present, for example, with lime.

It will accordingly be seen that by treating oil gas in the manner described, a mixture of ethylene hydrocarbons is obtained which can be used directly for the production of a "Dutch" liquid, of a relatively stable nature, substantially free from objectionable constituents such as the more unstable chlorinated hydrocarbons and otherwise of improved properties. Furthermore, the preliminary treatment of the oil gas results in the separation of the hydrogen and methane in a high state of purity so that they can be used directly in gas engines or for heating or illuminating purposes.

We claim:

1. The method of producing dichlorinated ethylene hydrocarbons from oil gas, which comprises subjecting the oil gas to a preliminary rectification and thereby separating the ethylene and propylene from the hydrogen and saturated and higher unsaturated hydrocarbons, and subjecting the resulting mixture of ethylene and propy- 130

lene to the action of chlorin in the presence of a co-solvent of both the chlorin and the hydrocarbons, whereby a mixture of dichlorinated ethylene and propylene is obtained 5 in a smooth and easily regulated manner.

2. The method of chlorinating ethylene hydrocarbons, which comprises introducing the same and chlorin separately into a body of a co-solvent of both the chlorin and the 10 ethylene hydrocarbons, whereby the chlorination is effected in a smooth and easily regulated manner.

3. The method of producing a mixture of dichlorinated ethylene hydrocarbons, which 15 comprises passing a mixture of ethylene hydrocarbons and chlorin separately into a co-solvent of the chlorin and of the hydrocarbons and thereby effecting the chlorination of the dissolved materials in a smooth 20 and easily regulated manner.

4. The method of producing from oil gas a mixture of dichlorinated ethylene hydrocarbons consisting principally of ethylene and propylene dichlorides, which comprises 25 subjecting the oil gas to a preliminary fractional liquefaction and rectification and thereby separating the ethylene and propylene from the hydrogen and methane and from the higher unsaturated hydrocarbons, 30 whereby a mixture of ethylene and propylene is produced relatively free from hydrogen and other hydrocarbons, and subjecting the resulting gaseous mixture to the action of chlorin by passing the gases and the chlorin 35 separately into a co-solvent of both the

chlorin and the hydrocarbons, which co-solvent contains dichlorinated ethylene hydrocarbons resulting from the reaction, whereby a mixture of dichlorinated ethylene hydrocarbons consisting principally of 40 dichlorinated ethylene and propylene is obtained in a smooth and easily regulated manner.

5. The method of chlorinating ethylene hydrocarbons, which comprises introducing the same and chlorin separately into a body of a co-solvent of both the chlorin and of the ethylene hydrocarbons, which co-solvent is made up of the dichlorinated ethylene hydrocarbons resulting from the reaction, 45 whereby the chlorination is effected in a smooth and easily regulated manner.

6. The method of producing a mixture of dichlorinated ethylene hydrocarbons consisting essentially of dichlorinated ethylene and 50 propylene, which comprises passing a gaseous mixture consisting essentially of ethylene and propylene, and chlorin, separately into a co-solvent of the chlorin and of the hydrocarbons, which co-solvent is made up of the chlorinated ethylene hydrocarbons produced during the reaction, whereby the chlorination of the mixture of hydrocarbons is effected in a smooth and easily regulated 55 manner.

In testimony whereof we affix our signatures.
